UNITED STATES PATENT OFFICE

170,260

FINGER PAD OR SIMILAR ARTICLE

Charles E. Jones, Chicago, Ill., assignor to The
Translon Company, Newark, N. J., a corpora-
tion of New Jersey

Application February 24, 1953, Serial No. 23,759

Term of patent 7 years

(Cl. D74—1)

To all whom it may concern:

Be it known that I, Charles E. Jones, a citizen of the United States, residing in the city of Chicago, county of Cook, and State of Illinois, have invented a new, original, and ornamental Design for a Finger Pad or Similar Article, of which the following is a specification, reference being had to the accompanying drawing, forming a part thereof.

Fig. 1 is a top plan view of a finger pad, showing my new design.

Fig. 2 is a bottom plan view.

Fig. 3 is an end elevational view, and

Fig. 4 is a side elevational view thereof.

I claim:

The ornamental design for a finger pad or
similar article, substantially as shown.

CHARLES E. JONES.
